E. C. ANGELL,
CONTAINER OR RECEPTACLE,
APPLICATION FILED AUG. 19, 1915.

1,160,561.

Patented Nov. 16, 1915.

Inventor
Edward C. Angell.
By his Attorney John C. Saifert

UNITED STATES PATENT OFFICE.

EDWARD C. ANGELL, OF NEW YORK, N. Y., ASSIGNOR, BY MESNE ASSIGNMENTS, TO SINGLE SERVICE BOTTLE CORPORATION OF NEW YORK, OF NEW YORK, N. Y., A CORPORATION OF NEW YORK.

CONTAINER OR RECEPTACLE.

1,160,561.

Specification of Letters Patent. Patented Nov. 16, 1915.

Application filed August 19, 1915. Serial No. 46,330.

To all whom it may concern:

Be it known that I, EDWARD C. ANGELL, a citizen of the United States, residing in the borough of Manhattan, in the city, county, 5 and State of New York, have invented new and useful Improvements in Containers or Receptacles, of which the following is a specification.

This invention relates to single service 10 receptacles or containers of paper, such as paraffined paper, for carrying liquids and the like, consisting of a strip of material rolled into tubular form, preferably conical, with the longitudinal sides or edges overlapping 15 and secured together, a dished or flanged circular end being secured in the larger end of the rolled paper to serve as the bottom, and the upper end being adapted to be pinched together or collapsed and secured 20 in such position.

It is the object of the present invention to provide an improved receptacle or container of this character, and particularly to improved method and means of securing the 25 overlapped sides of the rolled sheet, to close the upper end, and to secure the bottom in place.

In the drawing accompanying and forming a part of this specification, Figure 1 is a 30 front elevation of a receptacle or container with an embodiment of my invention applied thereto and showing the same in closed condition. Fig. 2 is a front elevation. Fig. 3 is a perspective view showing in full lines 35 the normal condition of the container when empty, and in dotted lines when it is collapsed, and being partly broken away to show the construction of the bottom. Fig. 4 is a plan view of the sheet of material 40 from which the tube is rolled up. Fig. 5 is a detail perspective view showing the manner of securing the overlapped sides by a clamping strip. Fig. 6 is a sectional detail of the upper end of the container to show 45 the manner of closing the same. Fig. 7 is a sectional detail to illustrate the manner of applying the clamping strip to secure the bottom. Fig. 8 is a perspective view of the upper portion of the container illustrating 50 the clamping strip secured to the inner surface thereof. Fig. 9 is a perspective view of the clamping strip shown in Fig. 8; and Fig. 10 is a top view to show the manner

of closing the upper end with the strip applied to the inner surface.

Similar characters of reference designate like parts throughout the different views of the drawing.

The use of the container to which my invention relates is for the purpose of carrying liquids and the like, and which are commonly known as "single service packages," said container after having been once used to be thrown away or destroyed. In the drawing I have illustrated a container of this type which in its original condition is of a tubular or truncated cone form, the larger end of which constitutes the bottom and the smaller end the top.

The container consists of a sheet of material rolled into tubular form as shown at 11, with the longitudinal edges overlapping. These edges are secured together in their overlapped relation by a clamping member 12 consisting of a strip of pliable metal having portions stamped out therefrom, as at 13, to form prongs, alternate prongs being offset as clearly shown in Fig. 5, to provide two sets or rows of prongs. These prongs are forced through the overlapped sides and upset, alternate prongs being upset or clenched in opposite directions firmly clamping and sealing the sides together.

The bottom of the container consists of a circular member 14 of paper, preferably somewhat heavier than the material of which the tube is made. This member is preferably dished, that is, it has an annular flange 15 adapted to lie contiguous to the inner surface of the rolled sheet with the edges of the flange 15 substantially flush with the bottom end of the tube. To strengthen the bottom and the tube adjacent thereto, and to assure the bottom from being forced out by the pressure of the contents of the container a clamping strip 16 similar to the clamping strip 12 engages outside of the container with its prongs forced therethrough, and the annular flange of the bottom and upset thereby securely fastening the bottom.

The open or top end of the container is adapted to be pinched together or collapsed and secured together in its collapsed condition. For this purpose I provide a pliable metallic strip 17 which may be similar to

the strip utilized to secure the sides together, but preferably having two sets or rows of prongs 18, 19, as clearly shown in Figs. 1, 2, 3 and 4. This strip is of a length less than 5 one half the circumference of the upper or open end of the container, and is adapted to be attached to the outer and at one side of the container adjacent the upper end. For this purpose both sets or rows of prongs are 10 forced through the material of the container and one set, preferably the lower row, upset or clenched to clamp the strip to the container, the other row of prongs, preferably the upper row, projecting through the material of the container, as clearly shown in Fig. 3. When the container is in this condition with the clamping strips 12, 16 and 15 17 applied thereto the whole is made impervious to liquid as by dipping into paraffin or 20 a paraffin bath until the whole is thoroughly coated or impregnated with the paraffin when it is removed, the paraffin congealing or hardening when the container is ready for use.

25 After the container has been filled and it is desired to close and securely seal the same, the upper end of the container is collapsed so that the portion of the container opposite the strip 17 will lie adjacent to said strip 30 when the prongs 18 are forced therethrough and clenched or upset, as shown in Fig. 6, a suitable clamping tool preferably being utilized for this purpose. To open the container the top with the closing member is 35 torn or cut off, and should only a portion of the contents be used and it is desired to again close the container it is only necessary to fold over the top the side sealing or clamping member 12 being made of pliable 40 metal readily retaining it in such position.

In Fig. 8 I have shown the clamping strip 17 as applied to the inner surface of the container. In this construction alternate prongs are stamped from the strip to project from 45 opposite sides in opposite directions as shown at 20 and 21, Fig. 9. In applying the strip the prongs 20 are forced through the material in the container and upset, and when the top of the container is collapsed 50 the prongs 21 are forced through that portion of the container opposite the strip as

shown in Fig. 10 and upset securely closing the same.

Having thus described my invention I claim:

55 1. A receptacle or container comprising a sheet of paper rolled into tubular form with the longitudinal sides overlapping and having one end closed, the other end of the tube adapted to be collapsed to close the same; a pliable metallic strip having prongs to secure the overlapped sides together; and a pliable metallic strip having two rows of prongs, both rows of prongs adapted to be passed through a portion of the container 60 adjacent the open end and one row of prongs upset to secure the strip outside of the container, and the other row of prongs when said end is collapsed adapted to pass through a portion of the container opposite 65 to the strip and be upset to close and secure said end; and a paraffin coating for the paper and applied metallic strips, substantially as and for the purpose specified.

70 2. A receptacle or container comprising a sheet of pliable material rolled into tubular form with its longitudinal edges overlapping; a pliable metallic strip having prongs to engage in said overlapped edges and be upset to secure said edges together; a flanged 75 circular member to engage in one end of the rolled sheet with the flange lying adjacent the inner surface of the tube to close one end; a pliable metallic strip having prongs to extend around the tube with the prongs 80 passing through the tube and the flange of the circular member and be upset to secure the circular member in place and close one end; a pliable metallic strip of a length substantially one-half the diameter of the tube 85 and having two rows of prongs, both rows of prongs adapted to pass through one portion of the tube and one row of prongs upset to 90 secure the strip to the container, and an impervious coating for the sheet with the applied strips, and said open end of the tube adapted to be collapsed and the other row of prongs forced through the portion of the container opposite to the strip and upset to 95 secure said open end of the container in closed condition.

EDWARD C. ANGELL.
